No. 823 190.

PATENTED JUNE 12, 1906.

L. ROSENBAUM.

SAD IRON.

APPLICATION FILED SEPT. 19, 1904.

UNITED STATES PATENT OFFICE.

LOUIS ROSENBAUM, OF ST. LOUIS, MISSOURI.

SAD-IRON.

No. 823,190.

Specification of Letters Patent.

Patented June 12, 1906.

Application filed September 19, 1904. Serial No. 224,940.

To all whom it may concern:

Be it known that I, LOUIS ROSENBAUM, a citizen of the United States, residing at the city of St. Louis, State of Missouri, have invented a certain new and useful Improvement in Sad-Irons, of which the following is a full, clear, and exact description, such as will enable others skilled in the art to which it appertains to make and use the same, reference being had to the accompanying drawings, forming part of this specification, in which—

Figure 1 is a vertical longitudinal sectional view. Fig. 2 is a plan view of the sad-iron proper, the handle-plate and burner being removed. Fig. 3 is an inverted plan view of the burner. Fig. 4 is a rear elevational view of the sad-iron. Fig. 5 is a transverse sectional view on the line 5 5 of Fig. 1, and Fig. 6 is a top plan view of the mixing-chamber.

This invention relates to a new and useful improvement in sad-irons, and particularly to that class wherein a combustible fluid is used as the heating medium.

The object of my invention is to provide a simple and efficient construction and one whereby I am enabled to use a less amount of combustible fluid and at the same time obtain a greater heat directly upon the part to be heated than has heretofore been accomplished in devices of this character with which I am familiar.

The essential features of this invention reside in the novel construction and arrangement of the mixing-chamber and in the novel manner in which the burner is secured in position; and, finally, the invention consists in the novel construction, arrangement, and combination of the several parts, all as will hereinafter be described and afterward pointed out in the claims.

In the drawings, wherein like characters designate like parts throughout the several views, 1 represents the base of the sad-iron proper, which is preferably a hollow metallic casting open at its rear end. This casting is provided with a plurality of draft-openings 2 in its side walls near the bottom thereof, above which and on the inside of said base-casting is formed a deflecting rib or flange 3. The upper face or wall of the base-casting is provided with openings 4, 4, and 5 for purposes hereinafter specified. I also prefer to form openings 6 near the top front edge of the base-casting for increasing the draft.

7 and 8 indicate screw-threaded bosses

formed on the top wall of the base-casting at the rear thereof, extending forwardly from the former of which for the greater portion of the length of said base-casting is a flange 9.

10 is the burner proper, which is preferably also a hollow metallic casting and which is adapted to fit within said base-casting, said burner having at its rear end feet or projections 11, designed to rest upon the bottom wall of the base. This burner is also provided upon its under face with a border-flange 12, (see Fig. 3,) through which flange and communicating with the interior of the burner is a plurality of jet-perforations 13, the foremost of which, 13^a, being preferably obliquely formed, whereby the flame of the ignited gas issuing from said opening is projected directly against the point 1^a of the bottom plate of the base-casting for obvious purposes.

14 indicates a hollow screw-threaded boss formed upon the forward upper portion of the burner and communicating with the interior thereof. (See Fig. 1.)

15 indicates what I will designate the "handle-plate," the handle 16 being preferably formed integral therewith.

17 is a mixing-chamber, also preferably formed integral with the handle-plate 15 and consisting of a chamber 18 open at its top, said mixing-chamber extending upwardly and forwardly from the forward end of said handle-plate. This chamber from its relatively large open upper end gradually decreases in size toward its base, where it leads into a screw-threaded hollow boss 19, arranged on the under side of and preferably formed integral with the handle-plate 15. (See Fig. 1.) At about the base of said mixing-chamber is formed a number of air-inlet openings 20, and upon the upper open end of said chamber is arranged a bridge-wall 21, having a threaded opening through which an ordinary gas-cock 22 on the end of a gas-supply pipe is secured. Projecting downwardly from the cock 22 into the mixing-chamber for some distance for well-known reasons is a nozzle 23, the gas-opening through said nozzle being of greatly-reduced diameter with respect to the diameter of the supply pipe. This nozzle 23 preferably terminates at about the level of or a little below the openings 20.

24 indicates a short section of pipe which has threaded engagement with the screw-threaded boss 19 and when the parts are as-

sembled is designed to pass through the opening 5 in the upper wall of the base-casting 1 and engage the screw-threaded boss 14 of the burner 10 to hold said burner firmly in position and also act as a communicating passage into said burner for the gas and air which have commingled in the mixing-chamber. Thus it will be seen that a very simple and practical means is employed for securing the parts together and at the same time holding the burner firmly in position within the sad-iron proper.

Interposed between the upper wall of the base-casting 1 and the handle-plate 15 and resting on the bosses 7 and 8 and the flange 9 are a metal deflector-plate 25 and an asbestos or some other non-heat-conducting lining 26, said plate and lining being held in position by means of screws 27, which screws also serve as a means for preventing lateral movement of the handle-plate. The deflector-plate 25 at the side of the base opposite to that upon which the flange 9 is formed is bent downwardly to deflect the heat and products of combustion away from the user of the sad-iron. By this construction the flange 9, together with the deflector-plate and non-heat-conducting lining, fully protects the operator or user of the iron from the heat, the opening formed between the deflector-plate and the top wall of the base-casting permits the products of combustion passing up through openings 4 to escape, and the downwardly-extending portion of the deflector-plate deflects said products away from the operator.

By the novel construction above described I bring the flexible supply-hose used in devices of this character out of interference with the arm of the operator, and by arranging the open-ended mixing-chamber above and over the burner and at an angle thereto I am enabled to utilize the atmospheric pressure of cold air in forcing the air into and through the mixing-chamber, the tendency of cold air to fall and the increased draft obtained by my construction producing a greater pressure within the mixing-chamber and more thoroughly forcing the gas within and through the burner, the ignited gas being projected directly upon the base of the sad-iron proper and the heating power of the gas being greatly multiplied by the increased draft so obtained. I thus secure a maximum amount of heat upon the part to be heated with a minimum amount of fuel.

I am aware that minor changes in the construction, arrangement, and combination of the several parts of my iron may be made and substituted for those herein shown and described without in the least departing from the nature and principle of my invention.

Having thus described my invention, what I claim, and desire to secure by Letters Patent, is—

65 1. In a sad-iron, the combination with a

hollow base open at one end and having air inlet and exhaust openings, of a burner fitting therein and extending substantially the length of said base, a handle-plate, a mixing-chamber on said handle-plate, and means 70 connecting said handle-plate to said base and providing a communicating passage between said burner and mixing-chamber; substantially as described.

2. In a sad-iron, the combination with a 75 hollow base open at one end and having air inlet and exhaust openings, of a burner fitting therein and extending substantially the length thereof, a handle-plate, a mixing-chamber on said handle-plate, a gas-supply pipe 80 leading into said mixing-chamber, and a pipe connecting said handle-plate to said base and providing a communicating passage for the mixed air and gas between said burner and mixing-chamber; substantially as described. 85

3. In a sad-iron, the combination with a hollow base-casting open at one end and also having air inlet and exhaust openings, of a hollow burner fitting therein and extending substantially the length thereof, a handle-plate for said base, a mixing-chamber on said handle-plate, a gas-supply pipe leading into said mixing-chamber, and means for holding 90 said handle-plate, base and burner together and providing a communicating passage between said mixing-chamber and burner; substantially as described. 95

4. In a sad-iron, the combination with a hollow base open at one end and having air-inlet openings in its sides and openings for 100 the escape of products of combustion at its top, of a burner fitting in said base and having a fuel-inlet opening in its top and jet-perforations in its bottom, a handle-plate for 105 said base, a mixing-chamber formed integral with said handle-plate and open to atmosphere at its upper end; and a pipe connecting said mixing-chamber and burner together and providing a communicating passage for the mixed air and gas therebetween; substantially as described. 110

5. In a sad-iron, the combination with a hollow base, of a burner fitting therein, said burner being provided with a hollow threaded boss, a handle-plate also provided with a 115 hollow threaded boss, a mixing-chamber on said handle-plate and leading into said boss thereon, and a pipe connection engaging the threaded bosses on said burner and handle-plate for providing a communicating passage 120 between the burner and mixing-chamber; substantially as described.

In testimony whereof I have signed my name to this specification in the presence of two subscribing witnesses.
